ELECTRIC DRY SHAVER

George G. Going, Stamford, Conn., assignor, by
mesne assignments, to Remington Rand Inc.,
Buffalo, N. Y., a corporation of Delaware

Application May 6, 1938, Serial No. 206,376

3 Claims. (Cl. 30—43)

This invention relates to improvements in the cutting head for razors of the dry shaver type, and particularly to the construction and arrangement of the cutter bars thereof.

In the past, attempts have been made to improve the cutting quality of electric dry shavers by reducing the thickness of the outer cutter to insure a close shave. In so doing the cutter bars were weakened and became bent and distorted, thereby causing the razor to cut and chafe the skin. Another undesirable feature inherent in razors of this type is the clogging of the blades with hair, thus slowing down the razor and preventing the entrance of hair into the slots between cutter bars. It has also been found that the cutter bars of the outer cutter extend parallel to the line of travel of the razor, and tend to brush or bend the hairs of the beard down against the face, thus preventing them from entering the slots between the bars to cut.

It is, therefore, the principal object of this invention to provide a cutting head in which the cutter members are so formed that the cutter bars of the outer cutter are located at an angle to the direction of travel thereby insuring that all of the hairs of the beard are brought into engagement with the shearing edges during one travel of the razor over the face.

Another object is to provide an inner cutter having blades formed by slots of a sufficient width to prevent the hair from becoming clogged therebetween.

A still further object is to provide an outer cutter having two cutting fields one specifically for long hair and the other for short hair or stubble.

Another object is to form a cutting head the inner and outer cutters of which are strong and rigid and principally the outer cutter in which the metal of the skin bearing portion has been reduced to a minimum thickness.

A more clear conception of the construction operation and further objects of the invention may be had from the following specification when read in conjunction with the accompanying drawings in which:

Fig. 1 is an end view of the upper portion of a razor embodying the invention;

Fig. 2 is a front elevation of Fig. 1;

Fig. 3 is an enlarged plan view of the invention showing the outer cutter;

Fig. 4 is a cross section taken along line 4—4 of Fig. 3;

Fig. 5 is a still further enlarged cross sectional view taken along line 5—5 of Fig. 3;

Fig. 6 is a plan view of the inner cutter; and
Fig. 7 is a side elevation of Fig. 6.

Like characters of references refer to like parts in all the drawings.

The shearing head of the invention comprises 5 an outer cutter 28 and an inner cutter 29 (Fig. 1) and is adapted for use with a razor having an electric motor in a shell or casing 20 forming a handle to which the head is removably secured by a set screw 22. The inner cutter is oscillated 10 by an actuating arm 24 and held in engagement with the outer cutter by the spring-pressed positioning pins 25 both of which are well known in the art, and therefore will not be described 15 herein.

The inner and outer cutters are substantially U or channel-shaped as shown in Fig. 4, and are formed of sheet metal. The top or skin engaging surface of the outer cutter 28 is formed with raised channel 26 running longitudinally of the 20 cutter in which slots are cut forming cutter bars 27. The slots are located at an angle to the longitudinal axis of the cutters and will be referred to as "diagonal slots" hereinafter. The top portion is formed integral with parallel side walls 25 31 which are secured at their ends to a base member 32 in any well known manner such as welding or riveting. The base is in the form of a block provided with a longitudinal slot 34 to accommodate the actuating arm 24, and apertures 35 30 through which the positioning pins 25 extend.

Slots are cut in the corners of the outer cutter forming cutter bars 36 which are perpendicular to the longitudinal axis of the cutter. The metal remaining between the slots forming bars 27 and those forming bars 36 provides a rib or reinforcing member 37 which tends to stiffen the entire cutter. In Fig. 3 it will be noted that the diagonal slots are narrower than those forming bars 36. The wider slots at the corners are provided 40 to permit the entrance of long hairs to the inner cutter and both of these portions containing the bars 36 are used for cutting long hair only. A groove 45 (Fig. 4) is cut in each of the vertical faces of the outer cutter to provide comb member 45 to guide long hair into the cutting head.

It will be noted in Fig. 3 that the end of one cutter bar 27 overlies the end of the next adjacent bar. This location of parts is used to insure that each individual hair of the beard will 50 be combed into the diagonal slots and thus cut in one passage of the razor over the face. The center portion of the outer cutter is used for shaving only.

The inner cutter is similar in shape to the outer 55

cutter except that the base 38 is provided with slot 39 adapted to be engaged by the actuating arm 24, and indentations 40 adapted to be engaged by the heads of pins 25.

5 6 Slots are cut in the corners of the inner cutter forming bars 41 (Fig. 6) which are similar to and correspond to the bars 36 of the outer cutter. The slots which form the bars 42 in the raised portion of the inner cutter extend at right angles 10 to the longitudinal axis of the cutter and are approximately twice as wide as those forming the bars 41, but the bars are approximately the same width (Fig. 5), as the bars 36 of the outer cutter.

10 15 It has been found that this arrangement of the cutter bars in the inner cutter is the most desirable, as the wide spacing permits easy access of the hair to the blades of the inner cutter and also prevents clogging of the cutter with hair.

15 20 It will be noted in Fig. 5 that the outer cutter has been ground away in the portion containing the cutter bars, thereby forming a thin outer cutting plate having raised portions 44 at the ends thereof. These portions tend to stretch the skin and thus prevent it entering the slots between the cutter bars at the same time raising the hair upright into position to be cut.

20 25 While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention

as hereinbefore set forth, and as hereinafter claimed.

What I claim as new, and desire to secure by Letters Patent, is:

1. In a cutting head for a dry shaver, a U-shaped outer cutter having a raised central portion, diagonal slots cut in said raised portion and transverse slots cut in the corners of the remaining portion, said slots forming cutter bars, said transverse bars being adapted to cut long hair 10 and said diagonal bars being adapted to cut short hair and an inner cutter of similar shape reciprocably mounted within said outer cutter.

2. In a cutting head for a dry shaver, a U-shaped outer cutter having a raised central portion, slots cut in said central portion to form cutter bars, slots cut in the corners of the unraised portion, the ends of said slots in said raised portion being independent of and in staggered relation to said remaining slots, the metal therebetween forming a reinforcement for said cutter and an inner cutter of similar formation reciprocably mounted therein.

3. In a cutting head for a dry shaver, an outer cutter, an inner cutter, said cutters being U-shaped with a central raised portion, diagonal and transverse cutter bars formed in said central portion of said outer and inner cutters respectively, transverse cutter bars disposed on each side of said raised portion in each cutter and longitudinal webs connecting said transverse bars to said central portion.

GEORGE G. GOING.
